UNITED STATES PATENT OFFICE.

JAMES BARTLETT HAMMOND, OF NEW YORK, N. Y.

SIGHT ATTACHMENT FOR TYPE-WRITERS.

No. 846,025.

Specification of Letters Patent.

Patented March 5, 1907.

Application filed March 10, 1906. Serial No. 305,393.

To all whom it may concern:

Be it known that I, JAMES BARTLETT HAMMOND, a citizen of the United States, residing at New York city, New York, have invented 5 certain new and useful Improvements in Sight Attachments for Type-Writers, of which the following is a specification.

My invention consists in a sight attachment for type-writers, particularly that form 10 known as the "Hammond," in which a key wheel or shuttle is employed in connection with a hammer and in which an inking-ribbon guide and a ribbon-shield are arranged between the type and the hammer or other 15 part coöperating therewith.

The invention consists in the features, combination, and arrangement of parts hereinafter described, and particularly pointed out in the claims.

20 In the accompanying drawings, Figure 1 is a sectional view of so much of the type-writer as is necessary to a complete understanding of my invention. Fig. 2 is a detail view showing the relation of the hammer, shuttle, 25 and ribbon-shield. Fig. 3 is a further detail view of the ribbon-shield and means for holding it down in place. Fig. 4 is a detail view of the ribbon-guide. Fig. 5 is a plan view of the anvil, shuttle, hammer, and parts associated therewith.

In these drawings the anvil 1, the hammer 2, and the shuttle 3 are of substantially ordinary and well-known form. The ribbon extends between spools 4 and 5 in rear of the 35 type on the shuttle, being guided by fingers 6 7, constituting a ribbon-guide, said fingers being carried by an arm 8, pivoted at 9 to the under side of the plate 10, which partly encircles the anvil, said plate being supported 40 by posts, as at 11, from the frame 12. The ribbon-guide arm 8 is curved to conform substantially to the curved side of the anvil and shuttle, and there is one of these arms, together with its guide-fingers, on each side of 45 the shuttle, as shown in Fig. 5. In rear of the ribbon a shield 13 is arranged, supported at its ends by pins or extensions 14 from the curved arms 15; which extend to the front of the machine and are pivoted at 16 to the frame part 10. These curved arms 15 overlie projections 17, extending vertically and thence horizontally beneath the said arms 15, said projections or fingers being secured to or forming a part of the curved arms 8 of 55 the ribbon-guide.

Normally the ribbon-guide, together with

the ribbon-shield, is in a depressed position, such as will enable the operator to clearly see the last line or letter printed. This position of the parts is shown in Fig. 2.

In order to elevate the ribbon to the plane of printing and also to elevate the ribbon-shield so that the opening 18 therein will come opposite the type to be printed and also 60 the end of the hammer, I arrange on each side of the machine a vertically-extending rod 19, the lower end of which is bent at 20 and rests upon a roller 21, carried by the space-frame 22 of substantially the same 65 form as is well known in the Hammond machine. At their upper ends these rods bear 70 against the under edge of the arms 8, so that when a key is depressed the vertical slide-rods 19 will be operated and the arms 8 swung upwardly to lift the ribbon into the 75 printing plane, and at the same time the fingers 17 will lift the curved arms 15, which will thereby raise the ribbon-shield to the proper position for printing, and as soon as the key is released these parts—i. e., the ribbon and ribbon-shield—drop below the printing plane, and the last word or letter printed will be within clear view.

It will be understood that the ribbon-shield and its carrying-arms may be swung 80 up out of the way when it is desired to adjust or inspect any of the parts around the printing-point, because the arms 15 simply rest upon the fingers 17. One of these fingers 85 may be provided with an adjustable bearing-point 23, Fig. 4, for the arm 15 to rest on, so that the ribbon-shield may be adjusted 90 vertically to its proper position. In order to hold the ribbon-shields down, I provide a retaining-hook 24 on one of the alinement 95 guides 25 with which the machine is provided and which guides extend from the frame part 10. The guide upon which the hook is carried is pivotally attached at 26 to the frame part 10 and is held in normal position by a spring 27, a screw 28, extending 100 through the slot 29, limiting the position of the said guide with the hook. When it is desired to swing back the arms 15 with the ribbon-shield, it is simply necessary to throw 105 the alining-guide toward the right to thus remove the hook 24 from over the shield-carrying arm 15, and then this may be thrown back. This hook may be adjustable, being pivoted at 30, Fig. 3, to the upwardly-extending 110 part 31 of the alining-guide, a screw 32, passing through a slot 33, serving to set the

hook in a position to which it may be adjusted. This hook will thus aid in accurately positioning the ribbon-shield.

I claim—

- 5 1. In combination in a type-writer of the class described, a shuttle, a movable ribbon-guide, a ribbon-shield and means for raising and lowering the guide and shield automatically as the keys are operated to expose the printing to view, said ribbon-shield being movable independently of the guide, substantially as described.
- 15 2. In a type-writer of the class described, a shuttle, a ribbon-guide, a ribbon-shield carried independently of the guide, means for raising and lowering the ribbon-guide as the keys are struck, the said ribbon-guide in turn causing the upward and downward movement of the ribbon-shield, substantially as described.
- 20 3. In combination in a type-writer of the class described, a shuttle, a ribbon-guide movable substantially in a vertical plane and comprising pivoted arms, a ribbon-shield, a pivoted support therefor, said sup-

port resting upon a part of the pivoted arms of the guide and means for raising and lowering the guide-arms as the keys are operated, substantially as described.

4. In combination a type-writer of the 30 class described, a shuttle, a ribbon-guide including pivoted arms, a ribbon-shield, pivoted supporting means therefor resting on a part of the pivoted guide-arms, vertically-movable rods for raising the pivoted supporting-arms and the space-frame for operating the rods, substantially as described.

5. In combination in a type-writer, a ribbon-guide, a ribbon-shield, a movable support therefor, means for raising the ribbon 40 guide and shield as the keys are struck and a catch for holding the movable support down, substantially as described.

In testimony whereof I affix my signature in presence of two witnesses.

JAMES BARTLETT HAMMOND.
